UNITED STATES PATENT OFFICE

IGNATIUS J. GOODE, OF BOSTON, MASSACHUSETTS

OAR LOCK

Application filed April 10, 1930. Serial No. 443,142.

The present invention relates to an oar lock and has for its prime object to provide a structure which enables a person handling an oar to place the same inside the boat with 5 ease as contrasted with the trouble usually had with the common form of oar lock.

This feature is particularly useful when the boat is approaching another object such as docks, wharves, and the like.

10 Another very important object of the invention resides in the provision of an oar lock of this nature which is exceedingly simple in construction, inexpensive to manufacture, easy to manipulate and install, thoroughly efficient and reliable in use and operation, and otherwise well adapted to the purpose for which it is designed.

With the above and numerous other objects in view as will appear as the description 20 proceeds, the invention resides in certain novel features of construction, and in the combination and arrangement of parts as will be hereinafter more fully described and claimed.

25 In the drawing:

Figure 1 is an inner side elevation of the oar lock embodying the features of my invention, Figure 2 is a horizontal section taken substantially on the line 2—2 of Figure 1, Figure 3 is a vertical section taken substantially on the line 3—3 of Fig. 1, and

30 Figures 4, 5 and 6 are perspective views of the three castings.

Referring to the drawing in detail it will be seen that the letter A denotes the gunwale 35 casting, the letter B denotes the stud casting, and the letter C denotes the bar lock or casting.

40 Referring to the drawing in detail and first to the casting A it will be seen that the same comprises an elongated plate 5 adapted to rest on top of the gunwale and to be fastened thereto by screws 6 passing through openings 7 in the ends thereof. A pair of transverse shoulders 8 are formed on intermediate portions of the plate 5 to rise therefrom in spaced parallelism and are formed on their inner sides with opposed grooves 9.

45 Arms 10 depend from the inner side of the plate 5 and terminate in sleeves 11. Openings 50 12 are provided in the intermediate portions

of the arms 10 so that screws 14 may be inserted therethrough into the boat.

The stud casting B is of a substantially L-shaped formation comprising a relatively long leg 15 and a relatively short leg 16. 55

The relatively long leg 15 has at its extremity sleeves 17 to receive hinge pin 18 the ends of which extend through the sleeves 11. A stud 19 is disposed perpendicularly on the leg 16 in a direction opposite to the leg 15. 60

The casting C includes a U-shaped body 20 depending from the bight portion of which is a sleeve 22 circumjacent the stud 19 to rotate thereon. The upper end of the stud is flattened to form a head as is indicated in Figure 3 to hold the casting C on the stud. 65 At the bottom of the sleeve 20 are oppositely disposed wings 23 one under each horn or side of the body 20.

70 Thus it will be seen that when the casting C is disposed as is shown in Figures 1 and 3 the wings 23 are disposed in the grooves 9 and thus the casting B cannot be swung inwardly to the dotted line position shown in Figure 3. However if the oarsman places his oar parallel with the boat or substantially so the wings 23 are swung out of the grooves 9 and therefore the oars and the castings B and C may be swung into the dotted line position shown in Figure 3 that is inside 75 the boat. Thus with a little practice an oarsman may soon become skillful.

80 It is thought that the construction, operation, utility and advantages of this invention will now be quite apparent to those skilled in this art without a more detailed description thereof.

85 The present embodiment of the invention has been disclosed in considerable detail merely for the purposes of exemplification 90 since in actual practice it attains the features of advantage enumerated as desirable in the statement of the invention and the above description.

95 It will be apparent that changes in the details of construction, and in the combination and arrangement of parts may be resorted to without departing from the spirit or scope of the invention as hereinafter claimed or sacrificing any of its advantages. 100

Having thus described my invention, what I claim as new is:

1. A device of the class described comprising a member adapted to be mounted on a gunwale and including a pair of portions having oppositely disposed grooves, a member hingedly mounted to the first mentioned member and having a stud adapted to be disposed between said grooved portion, and an oar lock swivelly mounted on the stud and having projections receivable in the groove.
2. A device of the class described including, in combination, a casting including a plate having a pair of shoulders with opposed grooves and arms depending therefrom terminating in sleeves, an L-shaped member including a relatively long leg and a relatively short leg, said relatively long leg terminating in sleeves to be registered between the first mentioned sleeve, a pin extending through said sleeve, a stud perpendicular to the short leg, an oar lock swivelly mounted on the stud and having oppositely disposed wings receivable in the grooves.

25 In testimony whereof I affix my signature.

IGNATIUS J. GOODE.
